UNITED STATES PATENT OFFICE.

JOHN SILVANNS REAVES AND JAMES GRAHAM WELLS, OF ANNISTON, ALABAMA.

DESIGN FOR A GROCERY-BIN.

47,806.

Specification for Design.

Patented Sept. 7, 1915.

Application filed June 7, 1915. Serial No. 32,775. Term of patent 14 years.

To all whom it may concern:

Be it known that we, JOHN SILVANNS REAVES and JAMES GRAHAM WELLS, citizens of the United States, residing at Anniston, in the county of Calhoun and State of Alabama, have invented a new, original, and ornamental Design for Grocery-Bins, of which the following is a specification, reference being had to the accompanying drawing, form a part thereof.

Figure 1 is a perspective view looking to-

ward the front of a grocery bin, showing our new design; and Fig. 2 is a similar view looking toward the rear thereof.

We claim:

The ornamental design for a grocery bin, as shown.

JOHN SILVANNS REAVES.
JAMES GRAHAM WELLS.
